UNITED STATES PATENT OFFICE.

FREDERIC A. PEESO, OF PHILADELPHIA, PENNSYLVANIA.

STRIPPER FOR PUNCHES.

SPECIFICATION forming part of Letters Patent No. 660,334, dated October 23, 1900.

Application filed March 9, 1900. Serial No. 7,970. (No model.)

To all whom it may concern:

Be it known that I, FREDERIC A. PEESO, a citizen of the United States, residing at Philadelphia, in the county of Philadelphia and

5 State of Pennsylvania, have invented certain new and useful Improvements in Strippers for Punches; and I do hereby declare the following to be a full, clear, and exact description of the invention, such as will enable others skilled in the art to which it appertains to make and use the same.

10 My invention relates to strippers for hand plate-punches; and my object is to provide a stripper that can be readily secured to and 15 detached from a punch.

The invention will first be described in detail and then set forth in the claims at the end of the specification.

In the accompanying drawings, which illustrate suitable embodiments of my invention, Figure 1 is a view of a hand plate-punch of well-known construction with my improved detachable stripper secured thereto, the same being shown in side elevation. Fig. 2 is an 20 other view of said punch turned at a right angle relatively to Fig. 1 and showing the under side of said stripper. Fig. 3 is a view similar to Fig. 1, but with the handles of the punch omitted and with the jaws and stripper in section. Fig. 4 is a view in side elevation of the stripper detached and showing a slight modification. Fig. 5 is an end view of the same looking toward its front end. Fig. 6 is an end view thereof looking at its opposite or 25 rear end. Fig. 7 is a plan view of the under side of the stripper. Fig. 8 is a top or plan view of the stripper, and Fig. 9 is a similar view with the stripper-tongue broken away to more clearly show the upper surface of the base 30 portion of the stripper.

Punch-stripers as heretofore made consist of a bifurcated tongue or plate either formed integral with the punch or connected to one jaw thereof by means of screws or 35 other similar attachment. The objection to all such strippers is that the punches to which they are to be attached must be provided with some special fitting. My improved stripper is free from this objection, as no fitting of the 40 punch whatever is necessary in order to secure the stripper thereto. On the contrary,

my stripper may be secured upon punches already in use without altering them in any way.

The preferred example of my improvement, 55 as shown in the drawings, consists of a stripper A, having a base portion B, a curved arm C, which is extended to form a bifurcated spring-tongue or stripper proper, D, and an arm or brace E. The base B of the attachment is formed with an opening b, through which passes the jaw F of the punch G, to which jaw the attachment is secured, the upper surface of the base resting against the outer or under surface of said jaw. The front 60 and rear ends of the opening b are preferably beveled and curved, as shown, in order that the opening may closely fit the jaw F. The arm or brace E of the attachment, which is located between the stripper-tongue D and 65 base B in this instance, is formed of the metal which is cut away from the bifurcated tongue D and on its outer or free extremity is provided with a notch d, adapted to partly embrace or engage the punch-jaw near its outer 70 end when the attachment is in place. The brace is preferably a spring-arm, and, while adapted to securely hold the attachment in place, also permits the same to be readily detached from the punch. The base B of the 75 stripper should be provided with a small opening b', which registers with the opening f in the female jaw F of the punch to which the stripper is attached, the object of this opening being to provide for the escape of the 80 punchings.

The stripper is applied to the punch by simply passing the opening b over the jaw F and springing the brace-arm E into engagement with said jaw F, as shown in Figs. 1 and 2. 90 By a simple reversal of these movements the stripper may be readily detached. It will thus be seen that I have provided a stripper capable of quick, easy, and simple attachment and removal from hand plate-punches without the 95 necessity of altering the punch or providing it with any special means of securing the stripper.

The punch represented in the drawings and to which my improved detachable stripper is 100 shown as applied is an ordinary hand plate-punch now in common use, particularly by

dentists. My invention herein shown and described was designed with special reference to this particular style of hand-punch, to which it may be attached and detached, as above 5 described, without in any manner altering the punch. It should be observed, however, that the attachment may be modified more or less to adapt it for attachment to other forms of hand plate-punches without departing from 10 the scope of my invention. To this end the dimensions and precise form of the attachment shown may be altered in various ways while still retaining the essential and novel features of my invention—to wit, an attachment 15 consisting of a base having an opening through which the jaw of a punch may pass, means, such as the brace-arm E, for engaging said jaw for holding the attachment in place, and a stripper-tongue. In other words, not 20 only can the general design of the attachment be varied, but the particular form of base, as well as the particular brace-arm and stripper-tongue, may be altered as desired to adapt the attachment for use with any form 25 of punch.

In the stripper shown in Fig. 4 the brace-arm is omitted and in lieu thereof a small set-screw e is provided for engaging the jaw F of the punch for the purpose of holding the attachment in place.

Detachable punch-strippers are of course

old and well known, and such I do not broadly claim as my invention; but

What I claim is—

1. A detachable stripper for hand plate-punches consisting of a base having an opening through which the jaw of a punch may pass, means other than said base for engaging said jaw for detachably holding the attachment in place, and a stripper-tongue, substantially as and for the purpose set forth. 35

2. A detachable stripper for hand plate-punches, consisting of the base having an opening through which the jaw of a punch may pass, a brace-arm for engaging said punch-jaw, and a stripper-tongue, substantially as and for the purpose set forth. 40

3. A detachable stripper for hand plate-punches consisting of a base, a curved arm connected to said base and extended to form 50 a bifurcated stripper-tongue, and a brace-arm for engaging the jaw of a punch and located between said base and said stripper-tongue, substantially as and for the purpose set forth.

In testimony whereof I affix my signature in presence of two witnesses.

FREDERIC A. PEESO.
